RAILWAY SIGNALING APPARATUS

Carl M. Backer, Pittston, Pa., assignor to The Union Switch & Signal Company, Swissvale, Pa., a corporation of Pennsylvania

Application August 1, 1939, Serial No. 287,731

4 Claims. (Cl. 175—320)

My invention relates to railway signaling apparatus, and particularly to signaling apparatus for signal systems using coded current.

Railway code signal systems using time spaced impulses of direct current have been proposed, the codes being either of the polarity code type or of the frequency code type. For example, in a polarity code system one code may consist of uniformly recurrent impulses of current of positive polarity, a second code may consist of uniformly recurrent impulses of current of negative polarity and such impulses of current alternately of positive and negative polarity may be used for a third code. In a frequency code type, the impulses of current may be all of the same polarity but of different rates, such as a rate of 180, 120 or 75 impulses per minute. Of course, a combination of different polarities and rates may be used if desired. Also, in such code systems it has been proposed to make the individual impulses of current of short duration, that is, the duration during which current flows is short as compared with the duration between successive impulses when no current flows. Current impulses of short duration are desirable because they can be made of relatively high peak voltage as an aid to reliable operation of the signal system without an excessive energy output from the current source which ordinarily is a battery. In such systems, a code following relay responsive to such impulses of current is normally biased to one position to which it is moved by its biasing element when no code current flows and is energized and operated to a second position while a code current impulse persists. Thus, the code following relay is operated to its second position for only a brief period in response to each individual impulse of current and is operated to its first position for a relatively long period between the successive impulses of current. In other words, the code following relay is operated at unequal "on" and "off" periods, the "on" periods when current flows being relatively short and the "off" periods when no current flows being relatively long. The decoding apparatus of such systems is selectively governed by the code following relay according to the different codes and a more satisfactory operation of such decoding apparatus is effected when the code following relay is operated at substantially equal "on" and "off" periods.

Accordingly, a feature of my invention is the provision of novel and improved means whereby a code following relay or device is operated with substantially equal "on" and "off" periods

5 in response to code impulses of current which are short in duration as compared with the duration between successive impulses. A further feature of my invention is the provision of code responsive apparatus of the type here involved which automatically obtains substantially equal "on" and "off" periods of operation over a relatively wide range of different code frequencies or rates. Again, a feature of my invention is 10 the provision of code responsive apparatus of the type here contemplated which is economical in construction and operation. Other objects and advantages of my invention will appear as the specification progresses.

15 I shall describe two forms of apparatus embodying my invention, and shall then point out the novel features thereof in claims.

20 In the accompanying drawing, Fig. 1 is a diagrammatic view of one form of apparatus embodying my invention when used with the train carried apparatus of a cab signal system. Fig. 2 is a diagrammatic view of a modification of the apparatus of Fig. 1 which also embodies my invention.

25 In each of the two views like reference characters designate similar parts.

30 Referring to Fig. 1, the reference characters *1a* and *1b* designate the track rails of a railway and to which rails code impulses of current are applied according to different traffic conditions of the railway. My invention is not concerned with either the means or the manner of applying the code impulses of current to the rails *1a* and *1b* and such apparatus is not shown for the sake of simplicity. A form of such code transmitting 35 apparatus that may be used is disclosed and claimed in an application for United States Letters Patent Serial No. 222,883 filed August 3, 1938, by W. P. Place for Signal systems and now Patent No. 2,197,414.

40 It is sufficient for the present application to point out that the track rails *1a* and *1b* are supplied with impulses of direct current of different polarity patterns to reflect different traffic conditions or are supplied with impulses of direct current of different code rates or frequencies to reflect different traffic conditions. In as far as the instant case is concerned the significant feature of such impulses of current is the fact that the individual impulses are of short duration as compared with the duration between successive impulses of the same code. Also that the duration between successive impulses of current may be different for different codes. To illustrate such circumstances, it may be pointed out that

when a code rate of 180 impulses per minute or 3 impulses per second is used, each code cycle is of substantially .33 second duration with current flowing (impulse of current) for, say, .05 second and no current flowing for the remaining portion of the cycle or about .28 second. Again, if a code rate of 75 impulses per minute or 1½ impulses per second is used, each code cycle is of .80 second duration with current flowing for, say, .05 second the same as before and no current flowing for substantially .75 second. Again, the impulses of current may be of either positive or negative polarity, the duration of the impulses and the rate of occurrence being the same for the different polarities. It will be understood, of course, that I do not wish to limit my invention to the code rates and duration of impulses cited above, and that other rates and durations may be used.

The reference characters 4 and 5 designate two train carried coils or inductors mounted on a train in the usual manner in inductive relationship with rails 1a and 1b, respectively. The two inductors 4 and 5 are connected together in such manner that the electromotive forces induced therein in response to a code impulse of current flowing in the rails are additive, and the two coils are connected across the input terminals of a detector-amplifier DA by means of wires 6 and 7.

The detector-amplifier DA may be of any one of several well-known types and it is shown conventionally only for the sake of simplicity since its specific structure forms no part of my invention. The detector-amplifier DA may be that shown in the aforementioned Place application Serial No. 222,883 where electron tubes of the controlled ionization type are used with the tubes normally non-conducting and rendered momentarily conductive in response to each of the individual impulses of current flowing in the track rails.

A train carried code following relay MR1 of the direct current neutral type is provided with two windings, the first winding being a pick-up winding 8 and the second winding being a holding winding 9. The pick-up winding 8 of relay MR1 is included in the output or anode circuit of detector-amplifier DA by means of wires 10 and 11. It follows that when no electromotive force is being applied from inductors 4 and 5 across the input terminals of the detector-amplifier DA, no current flows in the output circuit thereof and pick-up winding 8 of relay MR1 is deenergized so that the contact fingers 12 and 13 of that relay fall by gravity into engagement with back contacts 14 and 15, respectively. At least there is no attractive force applied to contact fingers 12 and 13 by magnetic flux created by winding 8. When an electromotive force is applied from inductors 4 and 5 to the input terminals of detector-amplifier DA in response to an impulse of current flowing in the track rails, an impulse of current momentarily flows in winding 8 of relay MR1 and that relay is energized to attract contact fingers 12 and 13 into engagement with respective front contacts 16 and 17. Consequently, the pick-up winding 8 of relay MR1 is momentarily energized in response to each code impulse of the rail current and relay MR1 is picked up and released once for each code impulse of current, the "on" period of relay MR1 during which contact fingers 12 and 13 engage the respective front contacts 16 and 17 being short as compared with the "off" period during which contact fingers 12 and 13 engage the respective back con-

tacts 14 and 15 because of the short duration of the code impulses of rail current.

The code following relay MR1 controls a decoding relay DR, the circuit for decoding relay DR including one terminal of a battery 18, front contact 13-17 of relay MR1, winding of relay DR and the opposite terminal of battery 18. Decoding relay DR is slow releasing in character and when periodically energized it remains picked up from one energizing impulse to the next. Decoding relay DR controls at its front contact 19 a signal circuit as desired. It is clear that with decoding relay DR receiving an energizing impulse of current only during the "on" period of code following relay MR1, it may not be effectively energized because of the short period the relay MR1 is picked up. That is to say, it is desirable that front contacts 13-17 of code following relay MR1 be retained closed for an interval long enough for the energization of decoding relay DR to build up to an effective value.

To increase the "on" period of code following relay MR1 so that the "on" period is substantially equal to the "off" period and a more satisfactory control of decoding relay DR is effected, I provide equalizing apparatus which retains the code following relay MR1 picked up for an interval after the impulse of current applied to the pick-up winding 8 ceases. This equalizing apparatus comprises condensers C1 and C2, a charging resistor R1, a discharging resistor R2, a by-pass resistor R3, holding winding 9 of relay MR1 and circuit connections with battery 18.

The equalizing apparatus can best be explained by describing its operation. During the "off" period of relay MR1 and its back contact 12-14 closed, the condenser C1 is charged from battery 18 by a circuit that can be traced from the positive terminal of battery 18 over resistor R1, back contact 12-14 of relay MR1, wire 20, condenser C1, wire 21 and to the negative terminal of battery 18. Also, condenser C2 is charged by a circuit which includes the positive terminal of battery 18, resistor R1, back contact 12-14 of relay MR1, wire 20, condenser C2, resistor R3, wire 22, holding winding 9 of relay MR1, wires 23 and 21 and to the negative terminal of battery 18. The quantity of charge created on condensers C1 and C2 depends, within limits, on the time back contact 12-14 of relay MR1 is closed. With the polarity of battery 18 as indicated by the plus and minus signs, the right-hand plate of condenser C1 and the lower plate of condenser C2 as viewed in Fig. 1 are positive and the left-hand plate of condenser C1 and the top plate of condenser C2 are negative.

When the pick-up winding 8 of relay MR1 is energized in response to a code impulse of rail current and relay MR1 is picked up opening back contact 12-14 and closing front contact 12-16, the condensers C1 and C2 are disconnected from battery 18 and are connected with the holding winding 9 of relay MR1 for discharge there-through, condenser C2 being also connected with a closed discharging circuit to be shortly described. The discharge current from condenser C1 tends to flow from its positive plate over wire 20, front contact 12-16 of relay MR1, resistor R2, wire 22, holding winding 9 and wire 23 to the negative plate of condenser C1. The discharge current from condenser C2 tends to flow from its positive plate over wire 20, front contact 12-16 of relay MR1, resistor R2, resistor R3 and to the negative plate of condenser C2. The discharge current from condenser C2 creates a volt-

age drop across resistor R2 which is of the same polarity as the voltage drop across resistor R2 as created by the discharge current from condenser C1. Hence, the discharge from condenser C2 increases the total IR drop across resistor R2 and such increase in the IR drop has the same effect as an increase in its ohmic resistance as far as the discharge current of condenser C1 is concerned. This action delays the discharge of condenser C1. Condenser C2 is shortly discharged so that the IR drop across resistor R2 lessens and condenser C1 then discharges more quickly. The connection of winding 9 is such that the discharge current flowing therein creates a magnetic flux that aids the flux created by the current impulse flowing in pick-up winding 8. Consequently, the flux created by winding 9 tends to retain the relay MR1 picked up. The parts are so proportioned and adjusted that relay MR1 is retained picked up by means of flux created through holding winding 9 for a period after the current impulse ceases to flow in the pick-up winding 8 and relay MR1 is operated with substantially equal "on" and "off" periods. If the code rate is that of 75 impulses per minute, the time back contact 12-14 of relay MR1 is closed is relatively long and the charges created on condensers C1 and C2 are correspondingly large so that relay MR1 is retained picked up by the discharge current through holding winding 9 for a correspondingly long period and substantially equal "on" and "off" periods of operation of relay MR1 obtains. Again, if the code rate is that of 180 impulses per minute, the time back contact 12-14 is closed is correspondingly short and the charges built up on condensers C1 and C2 are correspondingly small so that the discharge current retains relay MR1 picked up after the current impulse flowing in pick-up winding 8 ceases is correspondingly short and substantially equal "on" and "off" periods of relay MR1 obtains. Consequently, nearly equal "on" and "off" operation periods of relay MR1 are effected over a relatively wide range of different code frequencies.

In Fig. 2, the train carried inductors 4 and 5 are mounted in inductive relation with track rails 1a and 1b, and are connected with the input terminals of detector-amplifier DA the same as in Fig. 1. In Fig. 2, the code following relay means consists of a first code following relay LR whose operating winding 24 is interposed in the output circuit of detector-amplifier DA, and a second code following relay MR which is controlled by the first relay LR through equalizing apparatus embodying my invention. The equalizing apparatus of Fig. 2 comprises condensers C3 and C4; resistors R4, R5, R6 and R7; and connections with battery 13. The code following relay MR of Fig. 2 in turn controls at its front contact 25 decoding relay DR whose front contact 19 is interposed in a signal control circuit the same as in Fig. 1.

When no electromotive force is supplied from inductors 4 and 5 to the input terminals of detector-amplifier DA of Fig. 2, no current flows in the output circuit thereof and relay LR is de-energized closing its back contact 26-27. With relay LR thus released, condenser C3 is charged from battery 13 over a simple circuit which includes positive terminal of battery 13, resistor R6, back contact 26-27 of relay LR, resistor R4, condenser C3 and negative terminal of battery 13. When an electromotive force is applied from inductors 4 and 5 across the input terminals of

detector-amplifier DA in response to a code impulse of current flowing in the track rails, an impulse of current momentarily flows in the winding 24 of relay LR and that relay is picked up opening back contact 26-27 and closing front contact 26-28. With front contact 26-28 of relay LR closed, condenser C4 and winding 29 of relay MR are connected in parallel across the now charged condenser C3. To be explicit, condenser C3 discharges through condenser C4, resistor R7, front contact 26-28 of relay LR and resistor R4; and also through winding 29 of relay MR, resistors R5 and R1, front contact 26-28 and resistor R4. Since the current impulse operating relay LR is short, that relay immediately releases to reconnect condenser C3 with battery 13. The charge built up on condenser C4 now discharges through winding 29 of relay MR and resistor R5. Relay MR is thus picked up and retained energized for an interval after the impulse of current from the detector-amplifier DA ceases to flow in winding 24 of relay LR and relay LR releases. Condenser C4 soon discharges and relay MR is then released ready for the next code impulse. The extent to which condenser C3 is charged depends, within limits, on the time back contact 26-27 of relay LR is closed and hence the charge built up on condenser C4 in response to the discharge from condenser C3 is proportional, within limits, to the rate at which relay LR is operated, with the result that the time relay MR is retained energized in response to the discharge from condenser C4 due to the charging thereof by the discharge of condenser C3 is greater for the slower code rate than for the higher code rate. In other words, the relay MR is retained picked up for a longer period at the lower code rate than at the higher code rate. I have found that with proper proportioning of the parts the relay MR is operated with substantially equal "on" and "off" periods at both the 75 and 180 code rates. Furthermore, I have found that two code following relays when used as shown in Fig. 2 give substantially equal "on" and "off" periods and critical adjustment in resistances and capacitors are not necessary. Also, contact adjustments of the relays are not critical.

It is to be pointed out that resistors R6 and R7 are provided to prevent sparking at the contacts of relay LR. Hence, it is clear that resistances R6 and R7 may be omitted if desired. That is to say, the resistors R4, R6 and R7 of Fig. 2 may be combined into one resistance R4.

Although I have herein shown and described only two forms of apparatus embodying my invention, it is understood that various changes and modifications may be made therein within the scope of the appended claims without departing from the spirit and scope of my invention.

Having thus described my invention, what I claim is:

1. In combination, a relay having a first and a second winding and biased to a first position and operable to a second position when current momentarily flows in said first winding, a first and a second condenser, a source of direct current, a resistor, means including a contact of the relay closed at said first position to connect said condensers with said source to charge the condensers in parallel, means including said resistor and a contact of the relay closed at said second position to connect said first condenser with said second winding for energizing said relay after current ceases to flow in the first winding, and

said second condenser connected across said resistor over said last mentioned relay contact to prolong the discharge of the first condenser through said second winding.

2. In combination, a relay having a first and a second winding and biased to a first position and operable to a second position when current momentarily flows in said first winding, a first and a second condenser, a source of direct current, a first and a second resistor, means including said first resistor and a first position contact of said relay to connect said source with said condensers to charge said condensers in parallel, means including said second resistor and a second position contact of said relay to connect said first condenser with said second winding to energize the relay, and said second condenser connected across said second resistor over the last mentioned relay contact to increase the voltage drop across that resistor by the discharge from said second condenser to prolong the energization of said relay by the discharge from said first condenser.

3. In combination, a relay having a first and a second winding and a circuit controlling contact biased to a first position and operable to a second position when either or both of said windings are energized, a first and a second condenser, a source of direct current, a first and a second resistor; a first circuit including said first resistor and said first position of said contact to connect said source of direct current across said first condenser to charge the first condenser, said second condenser in series with said second winding connected across said first condenser to charge said second condenser in parallel with said first condenser by said first circuit, a second circuit including said second resistor and said second position of said contact to connect said first condenser to said second winding to energize the

second winding to retain the contact at its second position due to the discharge of the first condenser once said contact has been operated to said second position due to energization of said first winding, and said second condenser connected across said second resistor over said second position of said contact to control the rate at which said first condenser is discharged through the second winding.

- 10 4. In combination, a two winding relay biased to a first position and operable to a second position when either one or both of its windings are energized, means connected to one of said windings to momentarily energize said one winding to operate the relay, a first and a second condenser, a first, a second and a third resistor, a source of direct current, a first circuit including a biased position contact of said relay and said first resistor to connect said direct current source to said first condenser to charge the first condenser, said second condenser in series with said third resistor and the other one of said windings connected in parallel with said first condenser to charge the second condenser by said first circuit, a second circuit including an operated position contact of the relay and said second resistor to connect said first condenser to said other winding to energize said other winding by the discharge of the first condenser to retain the relay at its operated position, and said second condenser in series with said third resistor connected across said second resistor over said operated position contact of the relay to increase the voltage drop across the second resistor due to the discharge of the second condenser to prolong the energization of said other winding by the discharge of the first condenser.

CARL M. BACKER.
